Robert J. Petermann.
By Victor J. Evans, Attorney

UNITED STATES PATENT OFFICE.

ROBERT J. PETERMANN, OF NEW YORK, N. Y.

KNITTING DEVICE.

1,418,967.

Specification of Letters Patent. Patented June 6, 1922.

Application filed November 29, 1920. Serial No. 427,169.

To all whom it may concern:

Be it known that I, ROBERT J. PETERMANN, a citizen of the United States, residing at 362 East 156th Street, in the county 5 of Bronx and State of New York, have invented a new and useful Knitting Device.

The object of my said invention is the provision of a simple and advantageous knitting device through the medium of which 10 various woolen articles may be expeditiously and easily knitted by normal persons as well as those who are subnormal.

To the attainment of the foregoing, the invention consists in the improvement as 15 hereinafter described and definitely claimed.

In the accompanying drawings, forming part of this specification:—

Figure I is a side elevation of the knitting device constituting the best practical embodiment of my invention that I have as 20 yet devised.

Figure II is a top plan view of the same.

Figure III is an end elevation of the device—i. e., a view in elevation at right angles 25 to Figure 1.

Figure IV is an enlarged vertical section of the views taken in the plane indicated by the line A—A of Figure 2.

Figure V is a fragmentary plan view 30 showing the arrangement of the pegs 7.

Figure VI is an elevation of the needle employed by way of example to show means to lift yarn over pegs of the device.

Similar numerals and letters of reference 35 designate corresponding parts and features in all of the views of the drawings.

It is within the purview of my invention to form my novel device of wood, metal or other material or materials compatible with 40 its purpose.

Among other elements said device comprises a platform 1, preferably, though not necessarily, of general rectangular form. In the said platform 1 and extending 45 throughout the thickness thereof is a central vertical opening.

Disposed in the said opening and arranged in the same plane as the platform 1 and having its periphery spaced from the 50 wall of the opening in the platform is a circular disk 2. The said disk 2 is appropriately fixed to a pedestal 6 which, in turn, is fixed to a cross bar 5.

Fixed to and depending from the platform 55 1 are end walls 4 in the lower edges of which are notches 4*. These notches 4* re-

ceive the cross bar 5, and in the preferred embodiment of my invention the said cross bars 5 are detachably connected to the end walls 4 of the device by screws 5*, this provision being advantageous inasmuch as it 60 renders it feasible to readily disassociate the disk 2, pedestal 6 and cross bar 5, as a unit, from the remainder of the device.

In the preferred embodiment of the invention brace bars 3 arranged under the platform 1 and interposed between the end walls 4 are preferably employed, it being understood in this connection that the platform 1, end walls 4 and brace bars 3 may be connected together by glue or any other means appropriate to the character of the device.

It will be apparent from the foregoing that the platform 1 and the disk 2 afford working surfaces and describe the circles 75 B. B. shown in Figures 2 and 5. Carried by the platform 1 and the disk 2 and spaced apart in circles designated by C. C. in Figures 2 and 5 are pegs 7. The positioning of the said pegs at equal distances from each 80 other determines the size of the stitch.

In Figure 6 I show a device for lifting 85 wool over the pegs 7, the said device including a wooden handle 8 and an appropriately shaped shank 9.

The utilization of the pedestal 6 and the bar 5 in association with the end walls 4 and the means detachably connecting the bar 5 to the walls 4 constituting an important feature of my invention inasmuch as the arrangement of the said elements entirely below the platform 1 and the disk 2 leaves the upper surfaces of the platform 1 and the disk 2 entirely clear.

In the practical use of my device it will 95 be understood that the concentric sets of pegs 7 contribute to the products of a purling stitch in the article being knitted, the said pegs being fed with fabric, and loops being cast over the pegs with the device or 100 needle shown in Figure 6 or any other appropriate device. In this connection it will be manifest that the clear upper sides of the platform 1 and disk 2 contribute to free action on the part of the operator in feeding 105 yarn or wool to the pegs and casting loops of the wool.

Experience has demonstrated that my novel device is susceptible of being used to advantage for the knitting of woolen caps, 110 mufflers, wristlets, ties, hand bags, sweaters and the like.

Having described my invention, what I claim and desire to secure by Letters-Patent, is:—

1. A knitting device comprising a platform with a central circular opening therein extending throughout the thickness thereof, end walls fixed to and depending from the underside of the platform and having notches in their lower edges, a circular disk arranged in said opening of the platform and in the same plane as the platform and having its periphery spaced from the wall of the said opening, circular series of spaced pegs on the platform and disk and spaced from the annular opening between the opening wall and the periphery of the disk, a pedestal fixed to and depending from the disk, a cross bar fixed with respect to the lower end of the said pedestal and disposed in the notches in the lower edges of the end walls, and means detachably connecting said cross bar to said end walls.

2. A knitting device comprising a platform with an opening therein extending throughout the thickness thereof, a disk located in said opening and arranged in the same plane as the platform and with its periphery spaced from the wall of the opening in the platform, a frame at the underside of the platform, supporting means at the underside of the disk and detachably connected with said frame, a circular series of spaced pegs on the platform and the disk and spaced from the opening between the platform and disk.

3. A knitting device comprising a platform with an opening therein, a disk arranged in said opening and spaced from the wall thereof, circular series of spaced pegs on the platform and disk and spaced from the opening between the two, and a detachable coupling between the disk and the platform entirely below the upper surfaces thereof.

ROBERT J. PETERMANN.
